UNITED STATES PATENT OFFICE.

DANIEL D. LYONS, OF FARMINGTON, MINNESOTA.

LIFE-PRESERVER.

1,250,911.

Specification of Letters Patent. Patented Dec. 18, 1917.

Application filed July 12, 1917. Serial No. 180,096.

To all whom it may concern:

Be it known that I, DANIEL D. LYONS, a citizen of the United States, residing at Farmington, in the county of Dakota and State of Minnesota, have invented certain new and useful Improvements in Life-Preservers; and I do hereby declare the following to be a full, clear, and exact description of the invention, such as will enable others skilled in the art to which it appertains to make and use the same.

My invention has for its object to provide an extremely simple and highly efficient life-preserver that can be continuously worn by a voyager, and when worn, is inconspicuous, comfortable, and affords additional protection to the wearer against the cold.

To the above end, generally stated, the invention consists of the novel devices and combinations of devices hereinafter described and defined in the claims.

In the accompanying drawings, which illustrate the invention, like characters indicate like parts throughout the several views.

Referring to the drawings,

Figure 1 is a front view of the life-preserver;

Fig. 2 is a back view of the same, with some parts broken away and some parts sectioned;

Fig. 3 is a horizontal section taken through the life-preserver above the belt thereof and showing the air chamber therein inflated;

Fig. 4 is a fragmentary detail view, principally in section, taken on the line 4-4 of Fig. 3, on an enlarged scale;

Fig. 5 is a detail view in vertical section taken on the line 5-5 of Fig. 4;

Fig. 6 is a fragmentary view of the vest, on an enlarged scale, and showing one of the joints between two of the air compartments therein, the position of the outer side of the vest, when its air chambers are deflated, being shown by means of broken lines; and

Fig. 7 is a perspective view of the metal reinforcement for the belt.

The improved life-preserver is, as shown, in the form of a vest 8 made from suitable

air-tight and water-proof material, is intended to be worn in the same manner as an ordinary vest, and has the customary neck opening and arm holes. The vest 8 is open up the front and connected by 55 buckle-equipped straps 9, which, when open, permit the life-preserver to be put on or taken off, at will. It will be noted that the vest 8 is formed with double walls and the outer wall is secured to the front wall by 60 air-tight joints 10, at points in the center of the back and under each arm hole, thus dividing said vest into two front sections and two back sections, as shown in Fig. 3, and each of said sections affords a normally deflated air chamber 11.

The outer wall of the vest 8, at each joint 10, is folded outward upon itself and held by a plurality of vertically spaced straps 12 and these folded portions of the vest afford 70 the end walls of the sections thereof. When the air chambers 11 are inflated, the same will appear, as shown by full lines in Figs. 3 and 6 and by broken lines in Figs. 1 and 2, and when the said air chambers 11 are 75 deflated, the outer wall of the vest 8 and the walls 13 between the air chambers 11 will fold, as shown by broken lines in Fig. 6. When the air chambers 11 are deflated, the gaps between the air chambers 11, formed by 80 the double walls 13, will be held together by the straps 12, thus giving the life-preserver a neat appearance.

Formed as a part of the vest, 8, just below the air chambers 11, is a belt 14, having 85 double walls affording a casing, in which is placed an inner tube 15. The ends of the belt 14 are connected by buckle-equipped straps 16 and the inner tube 15 is provided with a transverse partition 17, dividing the 90 same into two compressed air compartments 18. In some instances, it might be desirable to use two inner tubes in place of the single inner tube with a transverse partition therein.

95 The air chambers 18 may be independently filled with compressed air through check valve-equipped stems 19, of well known construction. The front and back sections of the vest 8, on one side thereof, are inde- 100

pendently connected to the underlying compressed air chamber 18 by tubes 20. These tubes 20 extend vertically through the belt 14 and inner tube 15 and are connected thereto by air-tight joints. The upper ends 5 of the stems 20 extend through the bottoms of the air chambers 11 in the vest 8, and also have air-tight joints therewith. In the intermediate portion of each tube 20, is a 10 valve seat 21, which has direct communication with the respective compressed air chamber 18 through a port 22. The ports 22 are normally closed by stem-equipped valves 23 mounted in the seats 21 and are 15 in the form of inverted cones.

The stems of the valves 23 extend through the lower ends of the tubes 20 and are equipped with finger or push buttons 24, which are mounted in sockets formed in said 20 tubes. Coiled springs 25, encircling the stems of the valves 23, are compressed between parts in the tubes 20 and adjustable abutments 26 on said stems and yieldingly hold the valves 23 closed. Said abutments 25 are in the form of nuts and have screw-threaded engagement with the stems of the valves 23. Suitable packing 27 is provided for forming air-tight joints between the stems of the valve 23 and the tubes 20.

30 In case a voyager, wearing one of the improved life-preservers, finds it necessary to use the same, he simply presses upward with his fingers on the push buttons 24 to open the valves 23. With the valves 23 open, the compressed air in the chambers 18 rushes into the air chambers 11 and inflates the same. The amount of compressed air in the belt 14 must be sufficient to properly inflate the air chambers 35 11 and, at the same time, keep the belt itself inflated. By locating the push buttons 24 in pairs under each arm and arranging the same to open by an upward pressure, the movements required to open the valves 23 40 are extremely simple and natural.

To keep the inside of the belt 14 flat so that the same is comfortable to the wearer and snugly fits against his body, there is secured therein, a metal reinforcement. This 50 reinforcement comprises a multiplicity of links 28 flexibly connected and located in the inner longitudinal edges of the belt and stays 29 having their ends secured to the guides between the links, and which stays 55 keep the links vertically spaced.

The above described life preserver, while especially adapted for use in the water, is well adapted for aviators, and in which case gas will be substituted for compressed air. 60 The word "air" is herein used in the broad sense to cover "gas".

What I claim is:

1. A life preserver comprising a multi-compartment belt affording independent

compressed air chambers, a vest having a 65 plurality of normally deflated air chambers, and valve-controlled ports independently connecting the normally deflated air chambers with the air chambers in the belt.

2. A life-preserver comprising a vest provided with a normally deflated air chamber, and having a tubular belt affording a compressed air chamber, and a valve-controlled port connecting said two chambers. 70

3. A life preserver comprising a tubular belt having means for separably connecting the ends thereof, said belt having a transverse partition in its back dividing the same into two compressed air compartments, a vest having four normally deflated air 80 chambers spaced therearound, and valve-controlled ports independently connecting the normally deflated air chambers with the compressed air chambers, the valves in said ports being arranged in pairs substantially 85 under the arm holes in the vest.

4. A life-preserver comprising a tubular belt affording a compressed air chamber, a vest having a normally deflated air chamber, and a valve-controlled port connecting said 90 two chambers.

5. A life-preserver comprising a tubular belt affording a compressed air chamber, a vest having a plurality of normally deflated air chambers, and valve-controlled ports connecting the air chamber in the belt with the air chambers in the vest. 95

6. A life-preserver comprising a tubular belt affording a plurality of compressed air chambers, a vest having a plurality of normally deflated air chambers, and valve-controlled ports independently connecting the air chambers in the belt with the air chambers in the vest. 100

7. A life-preserver comprising a tubular belt affording a compressed air chamber, a vest having a plurality of normally deflated air chambers, and valve-controlled ports independently connecting the air chamber in the belt with the air chambers in the vest, the valves in said port being under strain to close. 105

8. A life-preserver comprising a tubular belt affording a compressed air chamber, the inner vertical wall of the belt being flat, a vest having a normally deflated air chamber, and a valve-controlled port connecting said two chambers. 115

9. A life-preserver comprising a belt having a compressed air chamber, a vest having a normally deflated air chamber, a valve-controlled port connecting said two chambers, and means for holding the inner vertical wall of the belt flat, said means including horizontal rods in the longitudinal inner edges of the belt and vertical stays connecting the same. 120

10. A life-preserver comprising a belt

having a compressed air chamber, a vest having a normally deflated air chamber, a valve-controlled port connecting said two chambers, the inner vertical side of the belt
5 having double walls and a metal reinforcement for holding the inner vertical side of the belt flat comprising flexibly connected horizontal links in the inner longitudinal

edges of the belt between said double walls and vertical stays connecting said links.

In testimony whereof I affix my signature
in presence of two witnesses.
